(57) **CLAIM**

The ornamental design for a grapefruit segment extractor, as shown and described.

DESCRIPTION

FIG. 1 is a left front top perspective view, showing my new design;

FIG. 2 is a front top perspective view, thereof, shown with environment;

FIG. 3 is a top plan view, thereof, the bottom plan view being a mirror image thereof;

FIG. 4 is a front elevation view, thereof;

FIG. 5 is a back elevation view, thereof; and,

FIG. 6 is a left side elevation view, thereof, the right side elevation view being a mirror image thereof.

The broken lines in FIG. 2, showing a fruit, are for the purpose of illustrating environment and form no part of the claimed design.
